UNITED STATES PATENT OFFICE.

ADOLF BELER, OF PITTSBURG, PENNSYLVANIA, ASSIGNOR OF TWO-FIFTHS
TO CHARLES H. PARSONS, OF JENIFER, ALABAMA, AND FRED HARTLEY,
OF PITTSBURG, PENNSYLVANIA.

GAS-BURNER.

SPECIFICATION forming part of Letters Patent No. 716,176, dated December 16, 1902.

Application filed September 10, 1902. Serial No. 122,879. (No model.)

To all whom it may concern:

Be it known that I, ADOLF BELER, a citizen of the United States, residing at Pittsburgh, in the county of Allegheny and State of Pennsylvania, have invented a new and useful Gas-Burner, of which the following is a specification.

This invention relates to gas-burners for heating, cooking, and other purposes; and it has for its object to provide a device of this class which shall possess superior advantages in point of simplicity, durability, and general efficiency and which shall be constructed especially with a view of preventing what is known as "back-lighting," which not infrequently occurs in burners of ordinary construction, especially when a draft of air wafts the flame back into the mixing-chamber or to the air-intake.

With this and other ends in view the invention consists in the improved construction, arrangement, and combination of parts, which will be hereinafter fully described, and particularly pointed out in the claims.

My present invention may be best described as an improvement of the device for which Letters Patent of the United States, No. 706,633 were granted to myself on the 12th day of August, 1902, although it may be found applicable to differently-constructed burners of the same class.

In the accompanying drawings, Figure 1 is a perspective view of a gas-burner constructed in accordance with my present invention, parts of the same having been broken away to expose the interior construction. Fig. 2 is a vertical sectional view of said burner.

Corresponding parts in the several figures are indicated by similar characters of reference.

As in my previous patent above referred to, I employ an inverted conical deflector 1, supporting a flame-spreader 2 and surrounded by a casing 3, the upper portion of which is flared outwardly and upwardly to surround the deflector 1, between the outer side of which and the inner side of the casing is left a narrow annular space 4, the width of which may be regulated by raising or lowering the said casing with relation to the deflector, or

vice versa. This adjustment may be effected by any suitable means. The lower portion of the casing is cylindrical, as shown at 5, and it supports at its lower end an air-intake funnel 6, above which the cylindrical portion 5 of the casing is provided with auxiliary air-intake openings 7, the effective area of which may be varied by means of a hood 8, having a cylindrical portion 9, that slides upon the exterior portion of the lower cylindrical part of the casing, where it is adjustable by means of set-screws 10, engaging slots 11 in the said cylindrical portion 9 or by other suitable means. The air-intake funnel 6, which is of truncated conical shape, has at its upper edge a short cylindrical extension 12, which forms a mixing-chamber for the air admitted through the intake 6 and the gas which is admitted from a supply nozzle or tip 13, which may be disposed below or underneath the intake 6, and which may, if desired, engage a diametrical cross-bar 14 of said air-intake funnel, said cross-bar being centrally perforated to receive and to rest upon the gas-nozzle. The cylindrical portion 5 of the casing is provided with an interiorly-disposed annular flange 15, which is flared upwardly and inwardly in a truncated conical shape and provided at its inner edge with a cylindrical upward extension 16. This flange 15 intercepts the air admitted through the auxiliary air-intakes 7 and causes it to commingle with the mixture of air and gas issuing from the mixing-chamber 12, and projects the ultimate mixture against the pointed lower end of the deflector 1, whence it passes upwardly through the annular space 4, issuing from which it is ignited and the flame projected upon the flame-spreader 2.

As is the case in my former patent, previously alluded to, the amount of air permitted to enter through the auxiliary intakes 7 is capable of being perfectly regulated, so that the exact quantity of air shall be permitted to enter into the burner which will cause the gas to burn with that clear steady blue flame which indicates perfect combustion; but in the event of a back draft the gas mixture will not reach the air-intakes and there become ignited, but will, instead, be deflected

into the pocket 17, formed between the annular flange 15 and its upward extension 16 and the walls of the cylindrical portion 5 of the burner-casing. It will thus be seen that 5 while perfect provision is made for the primary and auxiliary admission of air for the mixing of the same with the gas, and for the regulating of the admission of air through the auxiliary intakes, the danger of ignition 10 at either of the air-intakes is quite avoided.

It will be noted that the diameter of the opening of the inwardly and upwardly flaring flange composed of the members 15 and 16 is distinctly less than the diameter of the 15 cylindrical upward extension 12 of the air-intake funnel 6. The object of this is two-fold—namely, first, to throw the air from the auxiliary intakes directly in the path of the mixture escaping from the primary mixing 20 chamber, thus insuring a thorough commingling of the air and gas, and, secondly, to increase the area and capacity of the pocket 17, thus correspondingly increasing its efficiency 25 and certainty of action in case of back draft.

25 Having thus fully described my invention, what I claim is—

1. In a burner of the class described, an inverted conical deflector, a casing surrounding the same and having a downwardly-ex- 30 tended cylindrical portion, an air-intake funnel at the lower end of said cylindrical portion of the casing, auxiliary air-intakes in the casing above the intake-funnel, and an up- 35 wardly-flaring flange disposed within the cylindrical portion of the casing and terminat- ing above the upper edge of the intake-funnel.

2. In a burner of the class described, a cas- 40 ing, a deflector supported within said casing, an air-intake funnel at the lower end of said casing, a gas-supply nozzle disposed concentrically in the intake-funnel, auxiliary air- 45 intakes in the casing above the funnel, and an interiorly-disposed upwardly-flaring flange terminating above the intake-funnel and forming, between itself and the wall of the casing, an annular pocket.

3. In a burner of the class described, a cas- 50 ing, a deflector supported within said casing, an air-intake funnel at the lower end of said

casing, a gas-supply nozzle disposed concentrically in the intake-funnel, auxiliary air-intakes in the casing above the funnel, means for regulating the effective area of said auxiliary air-intakes, and an annular upwardly- 55 extending flange disposed within the casing above the auxiliary air-intakes and terminating above the upper edge of the intake-funnel.

4. In a burner of the class described, a cas- 60 ing, a deflector supported within said casing, an air-intake funnel at the lower end of said casing having an upwardly-extended cylindrical flange, auxiliary air-intakes in the cas- 65 ing above the funnel, means for regulating the effective area of said auxiliary air-intake, and an annular upwardly-extending flange disposed within the casing above the auxiliary air-intakes and having an upward cylindrical extension terminating at a point intermediately between the lower point of the deflector 70 and the upper edge of the cylindrical extension of the intake-funnel.

5. In a burner of the class described, an in- 75 verted conical deflector, a casing surrounding the same and having a downwardly-extended cylindrical portion, an air-intake funnel at the lower end of said cylindrical portion of the casing, auxiliary air-intakes in the casing above the intake-funnel, and an upwardly-flaring flange disposed within the cylindrical portion 80 of the casing, forming a passage of distinctly- smaller diameter than the passage in the intake-funnel and terminating above the upper edge of said intake-funnel.

6. In a burner of the class described, a cas- 85 ing, an air-intake funnel at the lower end thereof, auxiliary air-intakes above and sepa- 90 rate from the funnel and an inwardly and up- wardly extending flange interiorly upon the casing, said flange forming a restricted pas- sage of less diameter than the passage through the intake-funnel.

In testimony that I claim the foregoing as my own I have hereto affixed my signature in the presence of two witnesses.

ADOLF BELER.
